UNITED STATES PATENT OFFICE.

JOHN E. GAMBLE, OF EAST LIVERPOOL, OHIO, ASSIGNOR OF ONE-HALF TO
WILLIAM BRUNT, OF SAME PLACE.

BRICK-KILN.

SPECIFICATION forming part of Letters Patent No. 448,333, dated March 17, 1891.

Application filed January 31, 1890. Serial No. 338,716. (No model.)

To all whom it may concern:

Be it known that I, JOHN E. GAMBLE, a citizen of East Liverpool, in the county of Columbiana and State of Ohio, have invented 5 certain new and useful Improvements in Pottery-Kilns; and I do hereby declare the following to be a full, clear, and exact description of the invention, such as will enable others skilled in the art to which it appertains to 10 make and use the same.

My invention relates to an improvement in pottery-kilns, and has for its object to so construct the kiln that heat will be made to circulate throughout the entire kiln in such a 15 manner as to heat the same uniformly in all parts of its interior.

A further object is to produce a pottery-kiln so constructed and arranged that the interior thereof will be heated uniformly with 20 a comparatively small amount of fuel.

A further object is to provide a pottery-kiln having a dome or cone and so constructed that heat may be uniformly distributed throughout the interior of the kiln proper before entering the dome or cone, and providing 25 means in such dome or cone for regulating the draft through the kiln.

With these objects in view my invention consists in certain novel features of construction and combinations and arrangements of parts, as hereinafter set forth, and pointed 30 out in the claim.

In the accompanying drawings, Figure 1 is an elevation of my improved kiln, partly in 35 section. Fig. 2 is a view on the line $x-x$ of Fig. 1. Fig. 3 is an enlarged view illustrating a portion of the system of pipes or flues located in the base of the kiln.

A represents the kiln, over the crown C of 40 which a cone or dome E is located and left open at its apex. Located at the base and extending around the circumference of the kiln is a series of furnaces A', each furnace comprising a pit a, a grate b, and an opening 45 for a door c. Communicating with each furnace A' is a flue B, which flues extend upwardly within the kiln in close proximity to the wall of the kiln and preferably to points about midway between the top and bottom 50 thereof, openings g being made in the wall of the kiln just over the furnace-doors c for the

admission of air into the flues B, and other small air-holes g' may be made in the wall of the kiln above the flues B. The bottom F of the kiln will preferably be located a short distance from the ground and may be made of brick or other suitable material, and located a short distance above the bottom F is a floor F' thus producing a space F² between the bottom F and the floor F'. In the space F² 60 a series of pipes G is inserted, and consists of pipes h, pipes h', communicating at one end with the pipes h, and short pipes h², which connect the pipes h' at points between their ends. The pipes h, with which the remaining pipes of the system communicate, as above explained, are closed at their outer ends, and at their inner ends communicate with a central or main stack M, which, starting from the bottom F, extends centrally through the 70 kiln and through an opening in the crown C. This stack may be made of a series of sections secured together by tongues and grooves. The floor F' is provided with a series of perforations d, which communicate with the 75 pipes G. A rod or bar e is secured in the dome or cone E and adapted to extend across the center of the same, being provided at a point immediately over the stack M with a bracket e', which latter in turn supports a 80 pulley e². A cord or rope is passed over the pulley e², and has secured to one end a cap or damper D, the other extremity of the rope being carried out an opening or window i in the dome, by which means the damper D 85 is suspended over the outlet of the stack M, and may be readily operated from outside the kiln to regulate the draft of air through the same. Fires being built in the mouths or furnaces A', heat will ascend through the 90 flues B to the crown of the kiln, and then, being deflected by the concave interior surface of the crown, will descend to the floor F' and pass through the perforations d into the series of pipes G, from whence the heated 95 air passes into the stack M, through which it passes into the dome or cone E, and finally through the open upper end of the cone into the open air. An opening or doorway H is provided, through which persons may enter 100 to fill the kiln with pottery to be burned. An opening may, if desired, be made in the

crown C, through which the hot air may escape when it is desired to permit the kiln to cool off, the opening being normally closed by means of a plug b'.

5 Having fully described my invention, what I claim as new, and desire to secure by Letters Patent, is—

The combination, in a kiln, of the outer wall terminating at the top in a dome, furnaces arranged around the base of the wall, internal flues leading from the furnaces and terminating a suitable distance above the furnaces, base-flues constructed to receive the

heated air, and central stack having openings at the bottom communicating with the base-flues, said stack terminating in the dome of the kiln at its upper end, substantially as set forth.

In testimony whereof I have signed this specification in the presence of two subscribing witnesses.

JOHN E. GAMBLE.
